POPCORN VENDING MACHINE

Edward L. Schiavone, Silver Spring, Md.

Application March 31, 1955, Serial No. 35,310

Term of patent 14 years

(Cl. D52—3)

The figure is a view in perspective of a popcorn vending machine showing my new design.

The undisclosed side of the vending machine is substantially the same in appearance as the side shown in the drawing.

The display of the hermetically sealed bag of popcorn in the window of the vending machine is for illustrative purposes only.

I claim:

The ornamental design for a popcorn vending machine, as shown and described.
